APPLICATOR CAP

John J. Pahls, St. Louis, Mo., assignor to Anchor Cap & Closure Corporation, Long Island City, N. Y., a corporation of New York

Application May 17, 1932, Serial No. 611,784

8 Claims. (Cl. 91—67.2)

The present invention pertains to closure caps and packages, and more particularly to an improved applicator cap.

Various products, such as glue, cement, nail polishes and the like, require applicators for their proper use. It has not been found practical to supply such applicators independently of the package because the purchaser buys the package and fails to buy or obtain the applicator. 5 Various attempts have been made to combine an applicator with a closure cap or stopper. For certain products, such as nail enamel, it has been found desirable to use a quill having a brush at one end for applying the enamel to the 10 nails. The quill has very distinct advantages by reason of the fact that it is inexpensive, light in weight, and highly resistant to the chemicals in the enamel. Attempts to attach the quill to a closure cap have not been successful. The adhesives, in many cases, dry out and the quill becomes loose and, in other cases, the quill splits, rendering the brush useless. It is quite an annoyance for the quill or applicator to break before the nail enamel has been used up. Numerous 15 complaints have been made because of this defect, but the other advantages of the quill have caused manufacturers to continue to sell packages provided with quill applicators.

The present invention aims to provide an improved applicator cap, particularly applicable to quill applicators, although certain of its features may be utilized with other constructions, which will eliminate or minimize the above objectionable features.

35 An object of the invention is to provide an improved inexpensive applicator cap.

Another object is to provide an applicator cap with a quill applicator which is rugged in construction and fully capable of withstanding the 40 usage to which it may be subjected.

Another object of the invention is to prevent the splitting of the quill of the applicator during use thereof.

Another object of the invention is to permit 45 greater variations in the size of quills, without decreasing the efficiency and effectiveness of applicators formed therefrom.

Another object of the invention is to provide 50 a secure attachment between a closure cap and an applicator, particularly a quill type applicator.

Other and further objects of the invention will be obvious upon an understanding of the 55 illustrative embodiment to be described, or will be indicated in the appended claims, and various

advantages not referred to herein will occur to one skilled in the art upon employment of the invention in practice.

A preferred embodiment of the invention has been chosen for purposes of illustration and description and is shown in the accompanying drawing, forming a part of the specification, wherein

Fig. 1 is a sectional view, with parts in elevation, of an applicator cap embodying the present invention;

Fig. 2 is an exploded view, partly in section, illustrating the parts before they are assembled;

Fig. 3 is an enlarged fragmentary, sectional view illustrating details of the quill attachment with the end of the quill extending into the well 15 of the cap;

Fig. 4 is an enlarged view, similar to Fig. 3, of another construction embodying the invention;

Fig. 5 is an enlarged view, similar to Fig. 3, of a slightly different construction; and

Fig. 6 is a further modified embodiment illustrating the invention.

Referring again to the drawing, there is shown, in Fig. 1, a closure cap 1 having a cover portion 2 and a depending skirt 4, with screw threads 5 on the interior thereof adapted to engage and co-

operate with similar threads on a container to seal the cap thereon. A suitable gasket 6, made of cork, rubber, or other sealing material, may be utilized to secure a hermetic or liquid-tight seal

between the mouth of the container and the cover portion of a closure cap. Preferably, the closure cap is made from a moldable plastic material, such as phenolic condensation products, cellulose acetate molding compounds, and the like. At the 30 central part of the cover cap, there is provided a

depending extension 7 having a well, or aperture, 8 therein for the reception of the parts of the applicator.

An applicator 9 is provided having a brush 10, of camel's hair or the like, secured to one end thereof, the other end being tubular. Preferably, this applicator is made from a quill, or the like. A member 11 is provided having an enlarged end

12 adapted to fit snugly into the well 8 of the 45 closure cap and a reduced end 14 adapted to fit into the open tubular end of the applicator member 9. The size of the reduced end 14 is sufficiently small to permit it to fit relatively loosely

in the large size quills so that it will pass into 50 the smaller sizes without splitting the quills. The additional space in the larger size quills may be filled with cement 13, or other adhesive, to secure the member 11 to the quill. The end of the quill preferably abuts against the shoulder 15, 55

intermediate the small and large ends of the member 11.

The applicator 9 and member 11 secured thereto are adapted to fit into the well 8 of the closure 5 cap and to be secured therein by a suitable adhesive. If desired, the relative sizes of the enlarged end 12 and the well 8 may be such that the parts are held in position by friction, but preferably a good cement is used to hold the parts 10 rigidly together.

While the shoulder 15 may be beyond the open end of the well 8, so that the applicator 9 is held in position entirely by the member 11, preferably, as shown in Fig. 3, the shoulder 15 is within 15 the well so that the open end of the tubular applicator member 9 extends into the well and is held between the inner cylindrical surface of the well and the outer cylindrical surface of the reduced portion 14 of the member 11. By supporting 20 the quill on both sides, any tendency for the quill to split at the open end is eliminated. The friction between the well and the quill, as well as the friction between the quill and the member 11, assists materially in holding the quill in position 25 so that if the contents of the package attack the adhesives chemically, or if the adhesives dry out, the parts will tend to remain assembled.

As shown more particularly in Fig. 4, the inner surface of the open end of the well may be flared 30 outwardly, if desired, as shown at 16, to facilitate the application of the parts. This is particularly advantageous where the quill is inserted into the well. In such instances, greater variations in 35 size of the quill may be accommodated because the flared portion tends to guide the quill and reduce its diameter slightly when it is forced into the well.

A slightly different construction is shown in Fig. 5, wherein the member 11 may be cylindrical 40 and of substantially the same diameter throughout. Good results may be obtained with this construction, although the assembling operation is not as convenient as with the constructions shown in Figs. 1, 2, 3 and 4. It will be understood 45 that the member 11, in Fig. 5, should preferably fit loosely within the applicator quill to permit substantial variations in the size of the quills without splitting the quills during the assembling operation.

50 In Fig. 6, a substantially cylindrical extension 17, depending from the cover portion of the cap, is provided, having the applicator quill 9 telescoped thereabout. A sleeve 18 extends about the quill so that the quill is interposed between the inner extension 17 and the outer sleeve 18. In this construction, the outer sleeve, which may be made of any suitable material, reinforces and holds the lower end of the quill in position and eliminates any tendency for the quill to split. 55 Suitable adhesives or cements are preferably used in all of the embodiments to hold the parts securely in position. It will be understood, however, that in certain instances, the cements or adhesives may be omitted without impairing 60 materially the utility of the article.

In assembling the parts of the embodiment shown herein, the closure cap may be formed by the usual molding operations and the gasket 6, of cork or other material, may be inserted therein. 70 The applicator 9 may be assembled with the reinforcing or holding peg 11 and is then inserted into the well or aperture 8 of the closure cap. Adhesive is applied to the member 11, preferably before it is inserted into the quill 9, and adhesive 75 is likewise applied to the enlarged end 12 of the

member 11, or to the inner surface of the well 8 prior to the insertion of the member 11. The applicator is then an integral part of the cap, the cap forming a very convenient holder for the applicator. The assembled applicator cap is merely 5 screwed on a suitable container to form a completed package. The parts of the applicator cap may be assembled by the cap manufacturer, or delivered to the packer in unassembled state, as desired.

10

It will be seen that the above invention provides a very effective sealing cap, with an applicator rigidly secured thereto, which is unlikely to become dislodged during the use thereof. The peg 11 may be rigidly secured within the well 8 15 of the closure cap without danger of dislodgment and may likewise be secured to the open tubular end of the applicator 9. The long extension 14 reinforces substantially the applicator quill and prevents breakage thereof. The member 11 may be made of wood, bakelite, or similar materials, and is inexpensive. The assembling 20 operation is simplified rather than complicated by the additional element. The invention provides a very rigid construction which is fully capable 25 of withstanding the rough usage to which it may be subjected.

15

As various changes may be made in the form, construction and arrangement of the parts herein without departing from the spirit and scope of 30 the invention and without sacrificing any of its advantages, it is to be understood that all matter herein is to be interpreted as illustrative and not in a limiting sense.

35

Having thus described my invention, I claim:

1. In a device of the class described, the combination of a closure cap having a well extending downwardly from the underside thereof, a peg member extending into and secured to said well, and a quill adapted to be used as an applicator, 40 said quill being telescoped over said peg member and secured thereto, said peg member extending downwardly from said well a substantial distance and extending into said quill a substantial distance to reinforce the quill against transverse 45 bending and splitting when utilized as an applicator.

40

2. In a device of the class described, the combination of a closure having a well therein, a quill with one end thereof inserted into said well, and reinforcing means within said quill, said means extending downwardly into said quill and below the end of the quill inserted in said well to reinforce the quill, said means wedging the inserted end of the quill against the walls of the well to 55 hold the quill within the well.

50

3. In a device of the class described, the combination of a closure having an extension with a cylindrical surface adapted to receive the end of a quill, a quill having one end thereof inserted 60 into said extension, and a substantially rigid member having a cylindrical surface within said quill adapted to wedge the inserted end of the quill against the cylindrical surface of said extension to hold said quill therein, said member 65 extending downwardly into said quill a substantial distance beneath the extension to reinforce the quill against transverse bending thereof.

60

4. In a device of the class described, the combination of a closure cap having a hollow extension depending therefrom, a peg having an enlarged portion, said enlarged portion of the peg being secured in said hollow extension, and a tubular member adapted to receive a brush at one end to 70

75

serve as an applicator, the other end of said tubular member being secured to said peg and abutting against said enlarged part, said secured end of said tubular member being partially telescoped within said extension to prevent splitting thereof.

5. In a device of the class described, the combination of a closure cap having a depending extension with a well therein, a peg having a cylindrical portion of a larger external diameter at one end secured in said well and having a cylindrical portion of smaller diameter at the other end extending a substantial distance beyond said well, said peg being provided with a shoulder intermediate said smaller and larger portions, and
- 10 15 a quill having a tubular end fitting about said smaller portion of said peg, and having its free end abutting against the shoulder.

6. In a device of the class described, the combination of a closure having a depending extension, with a well in said extension, a member having an enlarged cylindrical upper portion fitting into said well and a reduced cylindrical portion extending beyond said well, a shoulder between said reduced portion and said enlarged portion, and a quill member having a tubular end fitting about said reduced portion and extending within the well, the extreme end of the quill member abutting against the shoulder and being held between the wall of the well and the outer surface
- 20 25 30 of said reduced end to prevent destruction there-

of, said parts being secured together by an adhesive.

7. A closure cap having an extension depending therefrom, said extension having a well therein, the surface at the open end of said well being flared outwardly, a member secured in said well, and an applicator having a tubular end inserted about said member with its extreme end intermediate the side wall of the well and the outer wall of said member, and an adhesive material intermediate the flared end of said well and the tubular end of said applicator member for securing the parts together.

8. In a device of the class described, the combination of a closure having a depending extension, said extension having a substantially cylindrical well therein provided with a flared portion, a member within said well, the space between said member and the flared portion at the side of said well being greatest at the open end of the well to facilitate the insertion of a tubular member therebetween, and a tubular applicator member having one end thereof telescoped about said first member and secured thereto, the end of said tubular member extending within the well, and said first member extending downwardly within said tubular member to reinforce said tubular member against transverse bending.

JOHN J. PAHLS. 30
